ATTORNEYS

UNITED STATES PATENT OFFICE.

ARTHUR MARTIN, OF PARIS, FRANCE.

DESIGN FOR WALL-PAPER.

SPECIFICATION forming part of Design No. 29,603, dated November 1, 1898.

Application filed October 7, 1898. Serial No. 692,957. Term of patent 7 years.

To all whom it may concern:

Be it known that I, ARTHUR MARTIN, of Paris, France, have invented and produced a new and original Design for Wall-Paper, of which the following is a specification, reference being had to the accompanying drawing, forming a part thereof, in which is represented a plan view of a section of wall-paper embodying the features of my design.

The design consists of a bouquet of roses encircled by festoons of ribbon intertwined

with jasmine, the ribbon being connected with the stems of the bouquet. At intervals the ribbon is formed into bows, and rose-buds are apparently held by the bows.

I claim—

The design for wall-paper herein shown and described.

ARTHUR MARTIN.
